REGULATED COIN RELEASED LOCKING
MECHANISM

Merrill Krakauer, Livingston, and Henry E. Verbeke, Chester, N.J., assignors, by mesne assignments, to Automatic Canteen Company of America, Chicago, Ill., a corporation of Delaware

Filed Jan. 18, 1960, Ser. No. 3,192
9 Claims. (Cl. 194—18)

Our invention relates to a regulated coin-released locking mechanism and more particularly to an improved coin-released locking mechanism, the operation of which is governed to ensure that it functions in its intended manner when actuated in response to the operation of a manually operated merchandising machine.

In coin mechanisms of the prior art employed on manually operated merchandising machines, the coins deposited in the machine as the purchase price of an article form part of the mechanical linkage for operating the machine. In machines of this type no problem exists of correlating the establishment of a credit corresponding to the sum in coins deposited in the machine with the sale price of an article. These coin mechanisms, however, have no provision for making change and are not adapted to permit the sale of a large number of articles at different various prices.

The copending application of Merrill Krakauer and Henry Verbeke, Serial No. 839,218, filed September 10, 1959, now Patent No. 3,107,000, discloses a Coin-Released Locking Mechanism which permits the sale of a very large number of articles selling at various prices while giving change to a customer in the event a sum in excess of the purchase price of a selected article is deposited in the machine. That copending application discloses two forms of the invention, one of which is applicable to an electrical merchandising machine and the other one of which is applicable to a mechanically operated merchandising machine. In the electrically operated form of the invention, a credit corresponding to the sum in coins deposited in the machine is established by the operation of a stepping solenoid which positions a switch contact arm at a position corresponding to the sum deposited in the machine. Owing to the fact that the credit is established in this manner and since the speed of operation of the machine is determined by the components of the electrical circuitry employed therein, this form of the machine operates with a high degree of certainty in the intended manner to give the correct sum in change.

In the mechanical form of the mechanism set forth in the copending application, a credit corresponding to the sum in coins deposited in the machine is established by a mechanical linkage. The operation of the change-maker and the movement of the escrow shelf in response to operation of the machine, all are under the manual control of the customer. Owing to this fact, improper operation of the mechanism is possible. That is, the dispensing mechanism may be operated fast or slow; the time of operation of the dispensing mechanism can be varied with reference to the time of deposit of coins; and the coin return mechanism as well can be manipulated. In the manual form of the mechanism shown in the copending application, if, for example, a quarter is deposited in the mechanism for the purchase of an article selling at 20¢ the machine may be unlocked slightly in advance of the establishment of the correct credit. If the customer actuates the dispensing mechanism quickly he will be given no change. It will be appreciated that upon the occurrence of this event an irate customer may either damage the machine or at least complain to the

2

management. Dishonest persons may claim to have been cheated out of change when in fact they have not been. For this reason it is imperative that the correct change always be given by the machine.

5 Other types of misoperation of the coin mechanism on a manually operated machine are possible. If, for example, the machine is operated after the normally locked mechanism has been freed and while the coins are still falling through the register the escrow shelf may return and catch these coins after the article has been delivered. Thus a customer can actuate the coin return mechanism and get his money back as well as the article of merchandise. It is also possible that a customer may obtain an article of merchandise, get his money back and also get 15 change.

We have invented a regulated coin-released locking mechanism which prevents misoperations of the type described hereinabove. Our improved coin-released locking mechanism ensures that the correct sum in change always 20 is given to the customer. Our machine is so constructed that a customer who inadvertently deposits more than the required sum in coins will not lose his money. Our machine prevents dishonest customers from obtaining merchandise without payment. Our machine prevents 25 dishonest customers from manipulating the mechanism in such manner as to obtain change in addition to merchandise without payment.

One object of our invention is to provide a regulated coin-released locking mechanism which overcomes defects 30 of known mechanical coin-released locking mechanisms.

Another object of our invention is to provide a regulated coin-released locking mechanism which ensures that the correct sum in change always is given a customer.

A further object of our invention is to forestall loss 35 to a customer of change resulting from a fast operation of the dispensing mechanism.

A still further object of our invention is to provide a regulated coin-released locking mechanism which prevents a dishonest customer from obtaining merchandise without 40 payment and from obtaining change where no change is to be given.

Other and further objects of our invention will appear from the following description:

In general our invention contemplates the provision 45 of a regulated coin-released locking mechanism having a time delay means for slowing the movement of a locking slide with respect to a credit registering slide when both slides move in response to the deposit of coins. This time delay means ensures that the proper credit is established before the operating mechanism is freed.

We provide our mechanism with a second time delay means for slowing the return of the escrow shelf to the position at which it receives coins after it has moved to the position at which coins on the shelf are accepted.

55 In the accompanying drawings which form part of the instant specification and which are to be read in conjunction therewith and in which like reference numerals are used to indicate like parts in the various views:

FIGURE 1 is a side elevation of our regulated coin-released locking mechanism.

FIGURE 2 is a fragmentary side elevation of our regulated coin-released locking mechanism.

FIGURE 3 is a fragmentary front elevation of our regulated coin-released locking mechanism with parts 65 removed and with other parts broken away taken along the line 3—3 of FIGURE 2.

FIGURE 4 is a fragmentary side elevation of one form of dispensing means with which our regulated coin-released locking mechanism may be used.

70 FIGURE 5 is a fragmentary side elevation of our regulated coin-released locking mechanism showing the change making means.

FIGURE 6 is a fragmentary rear elevation of our regulated coin-released locking mechanism taken along the line 6—6 of FIGURE 2.

Referring now to FIGURE 1 of the drawings, our coin-released locking mechanism indicated generally by the reference character 10 includes a coin slot 12 into which coins are deposited by a customer wishing to make a purchase. Coins deposited in the slot 12 first pass through a coin separator and slug rejector indicated generally by the reference character 14 of any suitable type known to the art such, for example, as that shown in the copending application of Christian Gabrielsen, Serial No. 469,183, filed November 16, 1954, now Patent No. 2,975,880. After passing through the coin separator and slug rejector 14, coins travel through a coin totalizer indicated generally by the reference character 16. This register 16 may be of any suitable type known to the art and preferably is the type shown in the Krakauer et al. application referred to hereinabove. As is explained more fully in the Krakauer et al. application, a quarter passing downwardly through the totalizer 16 actuates a feeler 18, a nickel passing downwardly through the totalizer 16 actuates a feeler 20, while a dime passing through the totalizer actuates the feeler 20 and a feeler 22. In response to actuation of the feelers 18, 20, and 22, a totalizer bar 24 moves downwardly through an aggregate distance which is proportional to the sum in coins which pass through the totalizer. The bar 24 drives a stud 26 through the same distance as that distance through which the bar 24 moves.

Referring now to FIGURE 2, the stud 26 extends through a suitable opening in the wall 28 of the mechanism and carries an eccentric bushing 30. Any suitable means such as a screw 31 adjustably positions the bushing 30 on the stud 26. Our mechanism includes a first locking slide 32, the lower end of which normally rests on the bushing 30. A pair of spaced guide bushings 34 and 36 carried by the wall 28 guide bar 32 for vertical sliding movement as viewed in FIGURE 2.

We employ any suitable means such, for example, as a screw 38 for securing a locking block 40 in a position on totalizer bar 32 corresponding to a base price with reference to which price differentials are provided in a manner to be described.

Referring now to FIGURE 4, one form of machine with which our coin-released locking mechanism may be used includes a frame indicated generally by the reference character 42 carrying a housing 44 which supports a plurality of plungers 46 having actuating knobs 48. When a plunger 46 is pulled in a direction outward of the machine or to the left as viewed in FIGURE 4, a dependent finger 50 on the plunger engages the machine operating bar 52 to slide the bar to the left as viewed in FIGURE 4 along slots 54 formed in the machine frame. As the bar 52 moves to the left as viewed in FIGURE 4, a cam plate 56 carried by the housing 44 moves a latch 58 into a position at which it engages the operating bar during the return movement of the plunger 46 to ensure return of the bar with the plunger. A pawl 59 rotatably supported on the operating bar is normally urged by a spring 62 into engagement with a rack 60 on the housing 42. This mechanism prevents return movement of the plunger 46, once its movement has been initiated, until the full outward stroke of the plunger is complete.

Movement of a plunger 46 outward of the machine initiates a dispensing operation of the machine with which our regulated coin-released locking mechanism is used. Since this machine per se forms no part of the instant invention it will not be described in detail. The details of one form of machine with which our mechanism is used are shown in the copending application of Christian Gabrielsen and Arthur R. Ericson, Serial No. 782,721, filed December 24, 1958, now Patent No. 2,996,217. It will be understood that our mechanism is not limited to

use with the machine shown in that copending application but may be used with a wide variety of machines dispensing articles or services.

We rotatably connect one end of a link 72 to the operating bar 52. A pin 74 connects the other end of link 72 to one arm 76 of a bell crank rotatably carried by a shaft 78 supported by the machine frame. A spring 80 coiled around shaft 78 normally urges the bell crank having arm 76 to rotate in a clockwise direction around shaft 78. One end of the spring bears against a bracket 82 carried by the frame 42 while the other end of the spring engages the other arm 84 of the bell crank. A pin 86 carried by the arm 84 is disposed in a slot 88 formed in one end of an actuating link 92 supported on a pin 94, carried by the machine frame, by means of a slot 96. A stud 98 is disposed in the other bifurcated end 100 of link 92. From the structure just described it will be seen that as a plunger 46 is moved to the left as viewed in FIGURE 4, it pivots the bell crank including arm 76 in a counterclockwise direction around shaft 78 and at the same time drives actuating link 92 upwardly to the left as viewed in FIGURE 4.

Referring again to FIGURE 2, a horizontal locking slide 102 carried by a guide 104 on the wall 28 and by a floating bushing 106 carries the pin 98. A plate 108 slidably supported on screws 110 or the like carried by wall 28 supports bushing 106. A flat spring 112 secured to the slide 102 by rivets 114 normally positions a locking pawl 116 on the slide 102 at a location at which it will engage the block 40 when the totalizer locking slide 32 is in that position which it occupies when no coins have been deposited in the machine. For purposes of clarity in order to show the relationship between the structure of FIGURE 2 and the machine structure shown in FIGURE 4, we have indicated the locking slide 102 in phantom in FIGURE 4.

Referring again to FIGURE 2, we form one end of a credit gear rack slide 118 with a slot 120 which suspends the slide 118 on the pin 26 carrying roller 30. A guide pin 122 carried by wall 28 rides in a slot 124 to guide the slide 118 in its movement. We employ any suitable means such as spacers 126 or the like for securing the credit gear rack 128 to slide 118. Rack 128 engages a pinion 130 rotatably supported on a shaft 132 carried by a price differential link 134. Pinion 130 engages a change-determining rack 136 slidably supported on studs 138 carried by wall 28. The studs 138 ride in a slot 139 formed in the rack 136. From the structure so far described, it will be seen that as coins pass through the totalizer 16, pin 26 and the bushing 30 carried thereby move downwardly as viewed in FIGURE 2 through a distance proportional to the sum in coins deposited in the machine. As the pin 26 moves downwardly, it drives the credit rack slide 118 downwardly through the same distance. Rack 128 drives pinion 130 to move the rack 136 upwardly through the same distance as that through which slide 118 moves downwardly in response to the deposit of coins in the machine.

As has been pointed out hereinabove, we so construct our machine that the full credit is established in the mechanism before the operating parts of the machine associated with the mechanism are freed. Referring now to FIGURES 2 and 3, we connect the upper end of the totalizer bar 32 to the piston wire 140 of an air dashpot assembly indicated generally by the reference character 142. Any suitable means such as a screw 144 screwed into a boss 148 carried by arm 32 secures the arm to the dashpot piston wire 140. The assembly 142 includes a sleeve or cylinder 150 formed of a material such as glass or the like and provided with a slot 152 in its wall. We secure a plate 153 provided with a port 155 over one end of the cylinder 150. A screw 157 threaded into the base 156 of the assembly 142 and into the plate 153 clamps a member 159 between the plate 153 and the base 156. We form member 159 with a flap 161 which overlies port 155.

The cylinder 150 receives a piston 154 carried by the wire 140. As the piston 154 moves into the cylinder 150 flap 161 permits air to pass through port 155 relatively freely. This air escapes through a port 163 in base 156. With slot 152 covered, as the piston moves outwardly flap 161 prevents the passage of air into the cylinder 150 through port 155. At the same time air is drawn slowly in around the edges of the clamped member 159 and into the cylinder 150 through a port 165 in plate 153. When the slot 152 is uncovered the piston again moves freely. Screw 157 may be adjusted to regulate the rate of flow of air into the cylinder through port 165. We initially position the piston 154 at a location at which its end face registers with slot 152.

From the structure just described, it will be seen that as the stud 26 carrying the eccentric bushing 30 moves downwardly, the credit establishing slide 118 moves downwardly owing to the direct connection between the stud 26 and the slide 118 provided by the slot 120. Thus a credit corresponding to the sum in coins deposited in the machine is immediately established. At the same time the totalizer locking slide 32 is permitted to move downwardly to move the locking block 40 downwardly out of the path of movement of the locking pawl 116 to free the operating parts of the machine. In our arrangement the rate at which the slide 32 is permitted to move downwardly is initially determined by the rate at which air is permitted to flow into the cylinder 150 through port 165. After a predetermined movement of the slide 32, piston 154 uncovers the opening 152 to permit the slide to move relatively freely. We have found that if we initially position the piston 154 at a location at which it uncovers the opening 152 after a movement corresponding to the basic coin such, for example, as a nickel, used in the machine, sufficient time delay is provided to ensure that the correct credit is established before the operating mechanism of the machine is freed. While we have shown an air dashpot assembly 142 as affording the required time delay, it is to be understood that we can, of course, employ any suitable time-delay means such as an inertial governor, an escapement or the like which are not shown since they are well known in the art.

Referring again to FIGURE 4, the sections of the machine with which our mechanism is used may be provided with price differential cranks 164 according as the sale price of the articles of a section is equal to the base price for which the mechanism is set or is different from the base price. We secure the crank arms 164 to a shaft 166 for rotation therewith. Shaft 166, which is supported in the machine frame, carries for rotation therewith an arm 180 the end of which is formed with an offset lug 182. When a plunger 46, corresponding to a machine section for which a price differential is provided, is actuated the finger 50 actuates the crank 164 to rotate shaft 166 in a counterclockwise direction.

Referring now to FIGURES 2 and 4 of the drawings, one form of price differential mechanism which may be used with our coin-released locking mechanism includes a price differential disk 186 rotatably carried on a shaft 188 on the wall 28. We form the disk 186 with a plurality of cam surfaces, the lowest surface 190 of which represents no price differential and the other surfaces of which represent various price differentials in multiples of the base coin such as a nickel used with the machine. For example, the respective surfaces 192, 194, 196 and 198 may correspond respectively to price differentials of 5¢, 10¢, 15¢ and 20¢. A spring 206 extending between a stud 202 on wall 28 and an offset lug 204 formed on price differential link 134 normally urges the link upwardly as viewed in FIGURE 2 to a position at which a roller 206 carried by a shaft 203 on the other end of the link engages a cam surface such as the surface 190 of the price differential disk 186. A stud 210 carried by wall 28 and disposed in a slot 212 in the price differential link 134 and a slot 214 in link 134 surrounding

5 shaft 188 guide the price differential link 134 in its movement. A spring 216 extending between a stud 218 on wall 28 and one of a number of offset lugs 220 carried by the price differential disk 186 normally urges the disk to rotate in a counterclockwise direction as viewed in FIGURE 2. For purposes of clarity in exposition, we have shown the price differential disk 186 in phantom in FIGURE 4 and have shown the actuating arm 180 in phantom in FIGURE 2. As will be apparent from these figures the lug 182 is adapted to engage one of a number of studs 222 on the disk 186 depending upon the price differential for which the disk is set. When arm 180 moves in a counterclockwise direction as viewed in FIGURE 4 or in a clockwise direction as viewed in FIGURE 2, arm 180 rotates the price differential disk 186 in a clockwise direction as viewed in FIGURE 2 to cause one of the cam surfaces on the price differential disk to move the link 134 downwardly through a distance proportional to the amount of the price differential.

10 From the structure thus far described, it will be apparent that upon the deposit of coins in the machine stud 26 moves the credit establishing slide 118 downwardly as viewed in FIGURE 2 through a distance proportional to the sum in coins deposited in the machine. 15 Owing to the connection between the credit establishing slide rack 128 and the change-determining rack 136 provided by pinion 130, rack 136 moves upwardly through a distance which is proportional to the aggregate sum in coins deposited. If the section corresponding to the selected article is provided with a price differential upon actuation of the associated plunger 46 disk 186 rotates to move link 134 downwardly through a distance proportional to the amount of price differential. Upon the occurrence of this movement, pinion 130 moves the change-determining rack downwardly through a distance proportional to the amount of the price differential to subtract this amount from the credit set up on the price-determining rack 128. Thus rack 136 has an overall movement which is proportional to the sum in coins deposited in the machine less the amount of the price differential.

20 Referring now to FIGURES 2 and 5, the change-determining rack carries a support 224 which extends through a suitable opening 226 in the wall 28. We provide support 224 with a plurality of holes 228 one of which receives a wire 230. Wire 230 is placed in that hole 228 which corresponds to the base price for which the machine with which our mechanism is associated is set. Wire 230 is adapted to provide a connection between the support 224 and a change-maker actuator 232 rotatably supported on a shaft 234 carried by the panel 28. 25 Wire 230 is adapted to engage a flange 240 formed on the actuator 232 after a predetermined movement upwardly of the support 224 as viewed in FIGURE 2. When the change-determining rack 136 and its support 224 have moved upwardly through a distance corresponding to the base price for which the machine is set, upon further movement upwardly of these members, wire 230 moves the actuator 232 in a counterclockwise direction as viewed in FIGURE 5.

30 We provide the actuator 232 with a lug 242 adapted 35 to engage an offset lug 244 of the change-determining cam 246 rotatably supported on a shaft 236 carried by an extension 237 on a change-maker drive slide 238 slidably supported on the mechanism frame. We form cam 246 with a number of surfaces 248 at various levels for determining the sum in change to be given a customer.

40 Referring now to FIGURE 2, the locking slide 102 carries a stud 250 which rotatably supports a roller 252. Roller 252 rides in a slot 254 formed in the end of an arm 256 rotatably supported on a shaft 258 carried by wall 28. When the locking slide 102 moves to the right as viewed in FIGURE 2 in response to operation of a plunger 46, roller 252 moves arm 256 in a clockwise direction about shaft 258 against the action of a spring 260 connected between a pin 262 on wall 28 and a pin 264 on the arm 256. A stud 266 on arm 256 rotatably sup-

ports a roller 268 which extends through an opening 270 in wall 28.

Referring again to FIGURE 5, roller 268 is adapted to engage bifurcations 270 and 272 formed on the end of a changer-operating lever 274 rotatably supported on a stud 276 carried by the wall 28. When roller 268 moves to the right as viewed in FIGURE 2, or to the left as viewed in FIGURE 5, it rocks lever 274 in a counter-clockwise direction as viewed in FIGURE 5 around stud 276. Upon return movement of the slide 102 lever 274 moves to its initial position. A stud 278 on the end of lever 274 is disposed in a slot 280 formed in an overload release link 282 rotatably supported on a stud 284 carried by a changer slide coupling arm 286 rotatably supported on stud 288 carried by the slide 238. A spring 290 connected between a pin 292 on the slide 238 and a pin 294 on the coupler arm 286 normally urges the arm to rotate in a clockwise direction as viewed in FIGURE 5. A spring 296 extending between a tab 298 on arm 286 and a tab 300 on link 282 provides a resilient connection between the link 282 and the coupling arm 286.

When arm 274 moves in a counterclockwise direction as viewed in FIGURE 5, stud 278 acts on link 282 first to tend to pivot coupling arm 286 in a clockwise direction as viewed in FIGURE 5. Under this action and under the action of spring 290, a lug 302 on the coupling arm 286 is brought into engagement with one of the surfaces 248 of the cam 246. After this engagement takes place, stud 278, acting through the overload connection provided by link 282 and by spring 296, moves the assembly including slide 238, link 282, arm 286, and cam 246 to the right as viewed in FIGURE 5. A spring 304 connected between a pin 306 on slide extension 237 and a lug 308 on the cam 246 normally positions the cam in engagement with the pin 306. A pendulous member 307 pivotally supported on a shaft 309 on wall 28 moves to engage a lug 311 on member 307 with teeth 313 on cam 246 upon jarring of the machine to prevent movement of the cam 246. This prevents a dishonest customer from obtaining more than the correct sum in change by jarring or tilting the machine.

The change maker of our mechanism includes a housing 310 carried by the wall 28. Housing 310 slidably supports a plurality of changer blades 312, each of which is adapted to be actuated to dispense a coin such as a nickel from a coin tube 314 carried by the wall 28. A flange 316 on the changer coupling arm 286 is adapted to engage one or more of the blades 312 depending upon the position of changer cam 246. When the slide 238 moves to the right, a number of coins such as nickels equal to the number of engaged blades are given to the customer in change. Since this change maker structure per se forms no part of the instant invention, it will not be described in detail herein. This structure is more fully shown and described in the copending application of Krakauer et al., Serial No. 26,881, filed May 4, 1960, for a Multiple-Slide, Single Reservoir Coin Dispenser.

Referring now to FIGURE 2 our mechanism includes a coin return plunger 318 slidably supported in a housing 320 carried by the wall 28. Any suitable means such, for example, as a pair of pins 322 or the like carried by the plunger 318 are adapted to engage one arm 324 of a bell crank pivotally supported on the wall 28 by means of a pin 326. We connect the other arm 328 of the coin return bell crank to a pin 330 carried by an actuating link 332. A pin 334, carried by link 332, is disposed in a slot 336 in the coin return link 338. A spring 340 connected to the pin 334 and to a pin 342 on the coin return link 338 provides a resilient connection between the link 332 and the link 338. A spring 342 extending between a guide bushing 344 carried by the wall 28 and a bracket 346 on link 338 normally urges the assembly upwardly as viewed in FIGURE 2. When plunger 318 is actuated to rotate the bell crank including arm 328 in a counterclockwise direction about shaft 326,

the coin return link 338 moves downwardly. A stud 348 on the link 338 supports a roller 350 adapted to engage a reset lever 352 rotatably supported on a shaft 354 carried by the wall 28 to pivot the lever 352 in a counter-clockwise direction upon downward movement of return link 338. As is explained more fully in the first Krakauer et al. application, referred to hereinabove, a spring 356 supported on a boss 360 on the lever 352 normally positions a reset lever 364 to permit it to reset the locking slide 32 and the totalizer and change-determining mechanism upon operation of the coin return lever. Another roller 366 rotatably carried on a shaft 368 on the arm 256 is adapted to actuate the lever 352 upon the occurrence of a dispensing operation to reset the parts of the mechanism.

Referring again to FIGURE 5, our mechanism includes a coin shelf 370 carrying a pair of stub shafts 372 and 374 which rotatably support the shelf in flanges 376 and 378 on the wall 28. A spring 380 extending between a pin 381 on flange 376 and on offset ear 382 on the shelf normally biases the shelf in a direction such that its upper portion tends to move outboard of the mechanism as viewed in FIGURE 5. The stud 348 on the coin return link 338 extends through an opening in wall 28 to support a member 384 having an extension 386 which cooperates with a plate 387 carried by shelf 370. We form plate 387 with a cam lug 388. Extension 386 normally prevents the shelf 370 from tilting under the action of spring 380. When the coin return link moves downwardly as viewed in FIGURES 2 and 5, the extension 386 moves downwardly through a distance which brings it out of engagement with lug 388 to permit the shelf 370 to tilt in a direction to return deposited coins to the customer.

The changer-actuating lever 274 carries a stud 390 which upon counterclockwise movement of the changer-actuating lever 274 strikes a cam 392 carried by the shelf 370 to pivot the lower edge of the shelf 370 outboard of the mechanism to cause coins deposited in the machine to fall into a suitable receptacle (not shown). This action of the mechanism in accepting or returning coins is more fully shown and described in the first Krakauer et al. application referred to hereinabove.

Coins such as quarters and dimes emerging from the totalizer 16 come to rest on a shelf portion 394 while coins such as nickels which are that denomination of coin which, in this form of our invention, is given in change come to rest on an inclined surface 396 of the shelf along which the coins are adapted to travel to replenish the supply of coins in the tube 314. Our mechanism includes an escrow lever 398 rotatably supported on a shaft 400 carried by wall 28. A spring 402 extending between an end of the lever 398 and a pin 404 on the coin chute assembly normally urges the lever to a position at which a lug 406 extending through an opening 408 in the coin chute cover 410 is positioned in the path of coins such as nickels on the surface 396. When the changer-actuating arm 274 moves in a counter-clockwise direction, a cam pin 412 on the bifurcation 270 pivots lever 398 in a clockwise direction to permit a coin to pass from the shelf surface 396 into the tube 314. At this time lug 406 actuates an escapement member 414 pivotally supported on a shaft 416 on the coin chute assembly to permit only a single coin to pass into the tube. A full supply lever 418 rotatably supported on the shaft 416 carries a feeler 420 which senses the presence of a full supply of coins in the tube. When there is a full supply of coins in the tube, a stop lug 422 moves into the path of nickels to prevent these coins from rolling to a position at which they may enter the tube 314.

As has been pointed out hereinabove, we provide our mechanism with means for regulating the movement of the coin shelf 370. Referring to FIGURES 5 and 6 any suitable means such as a screw 424 secures a crank arm 426 to the stub shaft 374 for movement therewith. We

mount a stud 428 on the end of crank 426 remote from shaft 374. Stud 428 receives the end of the piston wire 430 of an air dashpot assembly indicated generally by the reference character 432. Screws 434 secure a bracket 436 to the flange 378. The assembly 432 includes a sleeve or cylinder 440 formed of a material such as glass or the like and provided with a slot 442 in its wall. We secure a plate 438 provided with a port 443 over one end of the cylinder 440. Screws 439 secure a base 441 to the bracket 436. A screw 445 threaded through the base 441 and the plate 438 clamps a member 447 between base 441 and plate 438. We form member 447 with a flap 449 which normally overlies port 443. Cylinder 440 receives a piston 444 carried by wire 430. As the piston 444 moves inwardly of the cylinder 440 the flap 449 permits air to flow relatively freely through port 443. This air escapes through a port 451 in base 441. With slot 442 covered, as piston 444 moves out of the cylinder flap 449 prevents the flow of air into the cylinder through port 443. At the same time air flows slowly into the cylinder from around the edges of member 447 and through a port 453 in plate 438 with the result that movement of the piston 444 is slowed until slot 442 is uncovered. Screw 445 may be adjusted to regulate the flow of air around the edges of clamped member 447. We initially position the piston 444 in the cylinder 440 at a location at which the face of the piston is disposed between the edges of the opening 442. When the coin return mechanism is actuated to tend to rotate crank arm 426 in a counterclockwise direction as viewed in FIGURE 6, the piston is relatively free to move, drawing air through the opening 442 into cylinder 440. When the crank arm 426 is moved in a clockwise direction to accept coins, the initial movement of the shelf causes the plunger or piston 444 to expel air from the cylinder 440 first through the opening 442 and then through port 443 past the base valve flap 449 as opening 442 is covered. After coins have been accepted, spring 356 returns the shelf to its normal position. This action is delayed by the assembly 432 since air must be drawn over the edges of member 447 and through port 453 before piston 444 moves to a position at which the opening 442 is uncovered. This action, as will be explained hereinafter, prevents a customer from obtaining both merchandise without payment and change.

In operation of our regulated coin-released locking mechanism a customer deposits a sum in coins equal to at least the purchase price of an article into the mechanism through the coin slot 12. After having passed through the coin separator and slug rejector 14, the coins pass through the totalizer 16 to cause movement downwardly of stud 26 which movement is proportional to the sum in coins deposited in the machine. As can be seen by reference to FIGURE 2, this movement downwardly of the stud 26 produces a downward movement of the credit establishing slide 118 which is equal to the movement of the stud 26 owing to the direct connection between the slide 118 and the stud 26. Thus a full credit proportional to the sum in coins deposited in the machine is immediately established. As the bushing 30 carried by stud 26 moves downwardly, slide 32 is permitted to move downwardly. Its action is controlled by the air dashpot assembly 142. During the initial movement of the slide 32, air must be drawn into the cylinder 150 over the edges of member 159 at a rate determined by the setting of screw 157. When the slide 32 moves downwardly through a distance sufficient to uncover the opening 152, the slide 32 is relatively free to move to its final position determined by the position of bushing 30. In this manner the operating parts including the locking slide 102 of the machine are not freed until the full credit has been established. Upon actuation of an operating plunger 46, slide 102 moves to the right as viewed in FIGURE 2 and block 40 is out of the path of pawl 116 to permit an article to be dispensed. At the same time the correct

sum in change is given the customer depending upon the sum in coins he has deposited in the machine and depending upon the sale price of the article selected. As has been explained hereinabove, we initially position piston 154 to slow down slide 32 in its movement corresponding to a deposit of five cents, for example.

Referring now to FIGURES 5 and 6 coins which have been deposited in the machine are received by the coin shelf 370. When the dispensing mechanism is operated 10 in the manner described hereinabove, lug 390 strikes cam 392 to pivot the coin shelf 370 in a clockwise direction as viewed in FIGURE 6 to accept coins on the shelf. This action drives the piston 444 into the cylinder 440 to a position at which the opening 442 in the cylinder wall 15 is covered. The resetting of the coin shelf under the action of spring 356 is delayed owing to the fact that air must be drawn over the edges of the clamped member 447 of the assembly 432 before a piston 444 can return to a position at which the opening 442 is uncovered. 20 This operation prevents the coin shelf from being reset to catch coins which are still falling from the totalizer 16 toward the shelf 370 after the machine has been operated as might occur when an extremely rapid operation of the machine takes place. It will be appreciated that if 25 coins were caught by the shelf after a dispensing operation then the customer could actuate the coin return and obtain the money back along with the merchandise. It is possible also that where the sum deposited was such that change was to be given, the customer might get 30 his money back, an article of merchandise, and change.

It will be seen that we have accomplished the objects of our invention. We have provided a regulated, coin-released locking mechanism which overcomes the defects of mechanical coin mechanisms of the prior art. Our 35 mechanism ensures that a credit corresponding to the sum in coins deposited in the machine is set up before the machine parts are freed to prevent loss of change to a customer. Our mechanism has means for delaying the resetting of the escrow shelf to prevent a customer from 40 getting merchandise without payment or, merchandise without payment, his money back and change.

It will be understood that certain features and subcombinations are of utility and may be employed without reference to other features and subcombinations. This is 45 contemplated by and is within the scope of our claims. It is further obvious that various changes may be made in details within the scope of our claims without departing from the spirit of our invention. It is therefore to be understood that our invention is not to be limited to the 50 specific details shown and described.

Having thus described our invention, what we claim is:

1. In a merchandising machine, a dispensing mechanism comprising a member adapted to move in response to the operation of said mechanism a coin-released locking mechanism including means for normally locking said member, means responsive to the deposit of coins for establishing a credit equal to the sum in coins deposited, change maker means to be set by said credit establishing means to give change, said locking means being responsive to the deposit of coins and being adapted to release said member when a sum aggregating a purchase price has been deposited, means for retarding the releasing action of said locking means to ensure that said credit registering means has set said change making means to 55 give the correct sum in change before said locking means releases said member, a support, an escrow member adapted to receive and temporarily retain coins deposited in the coin-released mechanism, means mounting said escrow member for movement on said support from a 60 first position at which said escrow member receives coins to a second position at which coins received by said escrow member are accepted, means normally positioning said escrow member in said first position, means responsive to the operation of said dispensing mechanism for 65 giving the correct sum in change before said locking means releases said member, a support, an escrow member adapted to receive and temporarily retain coins deposited in the coin-released mechanism, means mounting said escrow member for movement on said support from a 70 first position at which said escrow member receives coins to a second position at which coins received by said escrow member are accepted, means normally positioning said escrow member in said first position, means responsive to the operation of said dispensing mechanism for 75 giving the correct sum in change before said locking means releases said member.

means for retarding the return movement of said escrow member to said first position under the action of said positioning means.

2. In a merchandising machine, a dispensing mechanism comprising a member adapted to move in response to the operation of said mechanism, a regulated coin-released locking mechanism including means for normally locking said member, means responsive to the deposit of coins for establishing a credit equal to the sum in coins deposited, change maker means to be set by said credit establishing means to give change, said locking means being responsive to the deposit of coins and being adapted to release said member when a sum aggregating a purchase price has been deposited and means for retarding the releasing action of said locking means to ensure that said credit registering means has set said change making means to give the correct sum in change before said locking means releases said member.

3. In a merchandising machine, a dispensing mechanism for dispensing at a purchase price, a regulated coin-released locking mechanism including means comprising a first movable member for normally locking said dispensing mechanism, means comprising a second movable member adapted to set up a credit corresponding to the sum deposited in said machine, change maker means to be set by said credit establishing means to give change, means responsive to the deposit of coins for moving said movable members and means for retarding the movement of said first movable member under the action of said coin responsive means to ensure that said credit registering means has set said change making means to give the correct sum in change before said locking means releases said member.

4. In a merchandising machine, a dispensing mechanism adapted to dispense for a purchase price and comprising a member adapted to move in response to the operation of said dispensing mechanism, a regulated coin-released locking mechanism including a locking slide for normally locking said movable member, means comprising a second slide for setting up a credit corresponding to a deposited sum, change maker means to be set by said credit setting up slide to give change, means normally positioning said locking slide and said second slide in respective positions at which said member is locked and in which said credit establishing means registers no credit, means responsive to the deposit of a predetermined value of coins for moving said locking slide and said second slide to respective positions at which said member is free to move and at which said credit establishing means registers a credit corresponding to the value of coins deposited and means for retarding the movement of said locking slide to ensure that said credit is established to set said change maker means to give the correct sum in change before said member is released.

5. In a merchandising machine, a dispensing mechanism comprising a member adapted to move in the course of a dispensing operation, a regulated coin-released locking mechanism including a credit registering slide, means responsive to the deposit of coins for moving said credit registering slide through a distance proportional to the sum in coins deposited, change maker means to be set by said credit registering slide to give change, a locking slide for locking said member, means normally urging said locking slide to move to a position at which said member is released, said coin responsive means normally positioning said locking slide to lock said movable member and means for retarding the movement of said locking slide with respect to the movement of said credit reg-

istering slide to ensure that said credit registering slide has set said change maker means to give the correct sum in coins before said locking slide moves to said position at which said member is released.

5 6. In a merchandising machine, a dispensing mechanism comprising a member adapted to move in response to the operation of said mechanism, a coin mechanism including a support, an escrow member adapted to receive coins deposited in said coin mechanism, means mounting said escrow member for movement on said support from a first position at which said escrow member receives coins deposited in the coin mechanism to a second position at which coins received by said escrow member are accepted, means normally positioning said escrow member in said first position, means responsive to movement of said dispensing mechanism member for moving said escrow member to said second position and means for retarding the return movement of said escrow member to said first position under the action of said positioning means.

20 7. In a coin mechanism, a frame, a coin receptacle, an escrow member adapted to receive and temporarily retain coins deposited in said mechanism, means mounting said escrow member for movement on said frame from a first position at which said member receives coins deposited in said mechanism to a second position at which coins received by said member are dropped from said escrow member to a coin receptacle, means normally positioning said escrow member in said first position, means for moving said member to said second position and means for retarding return movement of said escrow member to said first position under the action of said positioning means.

25 8. In a coin mechanism, a support, a coin box, an escrow shelf adapted to receive coins deposited in said mechanism, means mounting said shelf for movement from a first position at which said shelf receives coins to a second position at which coins received by said shelf are dropped to said coin box, means normally positioning said shelf in said first position, means for moving said shelf to said second position and means for retarding the return movement of said shelf to said first position under the action of said positioning means.

30 9. In a coin mechanism, a support, an escrow member, means mounting said escrow member on said support for movement to a first position at which coins on said shelf are accepted and for movement to a second position at which coins on said shelf are returned, means normally positioning said shelf in a third position intermediate said first and second positions at which said shelf receives coins, means for moving said shelf to said second position, means for moving said shelf to said first position and means for retarding the return movement of said shelf from said first position to said third position under the action of said positioning means.
